(57) **CLAIM**

The new and original design for a needle remover, as shown and described.

DESCRIPTION

FIG. 1 is a rear and right side perspective view (unfolded) of the new design for a needle remover;

FIG. 2 is a rear and left side perspective view (folded) of the new design for a needle remover.

FIG. 3 is a rear and left side perspective view (unfolded) of the new design for a needle remover;

FIG. 4 is a rear and right side perspective view (folded) of the new design for a needle remover.

FIG. 5 is a left side elevational view (unfolded) of the new design for a needle remover;

FIG. 6 is a top plan view (unfolded) of the new design for a needle remover;

FIG. 7 is a right side elevational view (unfolded) of the new design for a needle remover;

FIG. 8 is a bottom plan view (unfolded) of the new design for a needle remover; and,

FIG. 9 is a right side elevational view (folded) of the new design for a needle remover.

The dashed lines on the needle remover are provided for illustrative purposes only and is not intended to be a part of the invention.
